(57) **CLAIM**

The ornamental design for a rotary flow divider for seeding and planting implements, as shown and described.

DESCRIPTION

FIG. 1 is an isometric view of a rotary flow divider in accordance with the present invention;

FIG. 2 is a top plan view of the rotary flow divider of FIG. 1; FIG. 3 is a bottom plan view of the rotary flow divider of FIG. 1;

FIG. 4 is a side elevational view of the rotary flow divider of FIG. 1;

FIG. 5 is an end view of a first end of the rotary flow divider of FIG. 1;

FIG. 6 is an end view of a second end of the rotary flow divider of FIG. 1; and,

FIG. 7 is a cross-sectional view of the rotary flow divider of FIG. 1, taken at line 7-7 of FIG. 4.

1 Claim, 6 Drawing Sheets
